UNITED STATES PATENT OFFICE

CHARLES J. CARLSON, OF SEATTLE, WASHINGTON

MACHINE FOR REMOVING BOX COVERS

Application filed August 20, 1928. Serial No. 300,761.

My invention relates to a machine for removing covers from boxes, for removing nails from said covers, and disposing of said covers after they are removed from the boxes.

In industries where large numbers of packing boxes of uniform size are handled, it often requires a great deal of time and labor to remove the covers from said boxes by hand, and, further, often results in considerable breakage or damage to the covers, which is an economic loss. One instance where this condition arises in which the machine embodying my invention is especially useful, is in canneries, and this instance of use is especially referred to in the following specification, but it is to be understood that the machine is intended for all uses to which it is adapted.

In canneries, the empty cans are often shipped to the canneries in wooden boxes which have the top or cover boards nailed on. At the cannery, the box covers must be removed before the cans can be taken out for filling. In removing the box covers it is desirable to avoid damage to the boxes and the covers for the reason that said boxes and covers are later used as packing cases for the filled cans. Where the covers are to be removed from hundreds or sometimes thousands of these boxes each day, it requires several men for this work alone, and, in removing the covers by hand, a relatively large percentage of the box covers are split or broken, and thus rendered unfit for a second use on the boxes after the filled cans have been placed therein. Another objection to removing the box covers by hand is that the hand process is necessarily slow and often results in other departments in the cannery being obliged to wait for cans, thus resulting in serious loss of time. Canneries are often located in out of the way places as, for instance, the salmon canneries of Alaska, and these canneries are often short of laborers and their work is seasonal, the canneries sometimes operating for only a few weeks in the year and during this time operating at maximum capacity.

A primary object of my invention is to provide a machine of simple and efficient construction which will quickly and easily

remove box covers from boxes in a minimum amount of time, with very little labor, and with a minimum amount of damage to the box covers.

A further object is to embody my invention either in a simple hand-operated machine, made chiefly from wood, which can be built in any ordinary work shop, or to embody the invention in a fully automatic power-operated machine of all-metal construction made to withstand long and hard use.

Another object of the invention is to provide automatic means for removing the nails from the box covers after they are taken off the boxes and automatic means for disposing of the covers after the nails have been removed therefrom. This saves a large amount of time and labor in removing the nails, conserves the box covers by minimizing the splitting and breaking of the same, saves nails by removing said nails without bending, and conserves space by leaving the covers free from obstructions so that they may be stacked flat in superposed relation in a manner which is not possible if the nails are not removed.

The above mentioned general objects of my invention, together with others inherent in the same, are attained by the machine illustrated in the following drawings, the same being the preferred exemplary forms of embodiment of my invention, throughout which drawings like reference numerals indicate like parts:

Figure 1 is a view in side elevation of a machine for removing box covers, which is constructed in accordance with my invention;

Fig. 2 is a view of the same, partly in elevation and partly in section, on broken line 2, 2 of Fig. 1, showing the clamping mechanism partially clamped on a box;

Fig. 3 is a fragmentary view similar to Fig. 2 except that only one side of the machine is shown and the clamping levers are in fully clamped position;

Fig. 4 is a detached plan view of one of the cover lifting members;

Fig. 5 is a detached plan view of one of the box gripping members;

Fig. 6 is a view partly in section and partly in elevation showing a modified form of the invention;

Fig. 7 is a view in elevation with parts shown in section of an improved and fully automatic machine constructed in accordance with my invention in which means is provided for removing the nails from the covers and for disposing of said covers after the 10 nails are removed therefrom;

Fig. 8 is a similar view taken at right angles to Fig. 7, parts being shown in section substantially on broken line 8, 8 of Fig. 7;

Fig. 9 is a fragmentary sectional view on a larger scale of the cover lifting and holding devices at one side of the machine; and

Figs. 10, 11 and 12 are detached views illustrating details of a nail puller and box lid lifter respectively, which are embodied in the fully automatic machine.

Referring to Figs. 1 to 5, I show a machine for removing the lids of packing boxes embodying an upright frame, preferably composed of four posts 11 arranged in rectangular formation and supported on base frame members 12 and 13. Inclined braces 14 are provided between the uprights 11 and base members 12 to assist in forming a rigid and substantial frame structure. The top of the frame is held rigid by rods 15 which extend crosswise in one direction and brace members 16 and 17 which extend crosswise at right angles to the rods and are made fast to the frame by the rods 15, said braces constituting spaced apart guide members as hereinafter described.

At a convenient height from the floor, I 40 provide a box support formed of two spaced apart angularly shaped members 18, which rest on cross bars 19 that are secured to the frame. The members 18 constitute a trackway for supporting boxes 20, one of which is shown by dot and dash lines in Fig. 2, while the lid or cover 21 is being removed from said boxes.

The mechanism for gripping and holding the box and the mechanism for lifting the 50 box cover is operatively disposed between the two posts 11 at each side of the machine, so as to engage with the two ends of the boxes which are placed on the trackway 18, as more clearly shown in Fig. 2. The box gripping and holding mechanism comprises two gripping levers or members 22 and 23, fulcrumed on pivot rods 24, each gripping member being relatively wide at its top end and narrower at its bottom end and being provided 60 on its inner side, above its respective pivot 24, with a box gripping element 25 having teeth 26, see Fig. 5, that are adapted to enter the ends of the box 20 to prevent said box from being lifted in the operation of removing 65 the box cover 21.

At their lower ends, the box gripping members 22 and 23 are tapered or narrowed, chiefly from one side, and are provided, nearer their left-hand edges as seen in Fig. 1, with slots 27 for the reception of levers 28 and 29 respectively, which are secured to the box gripping members by pivots 30 and serve as toggle links for swinging the box gripping members on the pivots 24. The toggle levers 28 and 29 are connected with each other by a pivot 31, and the toggle lever 29 extends outwardly to one side of the machine so that it may be readily grasped for operating the same. In Fig. 3, the levers 28 and 29 are shown between their two extreme positions. The inner end of the lever 29 carries a weight 32, preferably of lead, for bringing said lever and the parts connected therewith back to the retracted position, and further has a stop member 33 for arresting the movement of said levers and stopping the same in a gripping position, the middle pivot 31 being allowed to just pass the line of centers of pivots 30, whereby the levers will be locked in said gripping position, as shown in Fig. 3. Automatic means, hereinafter described, are provided for releasing or tripping the levers 28 and 29 from the locked position.

The means for removing the box covers comprises two relatively wide flat cover lifting members 34 and 35, having their upper ends slidable vertically between the guides 16 and 17 at the top of the frame and having blocks 36 and 37 on their outer sides. The bottom ends of the lifting members 34 and 35 and the bottom ends of the blocks 36 and 37 are jointly recessed to afford receptacles 38 into which tongue portions 39 on the upper ends of the box gripping members 22 and 23 project. This arrangement causes the lower ends of the cover lifting members to be moved toward and away from the box along with the upper ends of the box gripping members and, at the same time, leaves the cover lifting members free to be moved vertically.

The cover lifting elements 40, which actually enter between the top edges of the boxes and the box tops 21, are secured to the inner sides of the members 34 and 35 and extend horizontally across the same, and are preferably provided with teeth 41 as more clearly shown in Fig. 4. When the bottom ends of the members 34 and 35 are at the limit of their outward movement, these lifting elements 40 will be clear of the box and as the bottom ends of said members 34 and 35 are swung inwardly, these lifting elements will be caused to enter between the top edge of the box and the bottom side of the cover, (see Fig. 3), so that upward movement of the members 36 and 37 will lift the top from the box. For positioning the cover lifting elements 40, so that they will always enter accurately between the top edge of the box 20 and the box cover 21, and will not damage

either the box or the cover, I provide two stops 42, preferably of rubber, which are carried on blocks 43 that are secured to the respective members 34 and 35. The box 5 covers 21 are all of substantially the same thickness, and the rubber stops 42 will always come to rest on the top surfaces of such box covers, thus positioning the elements 40 accurately.

10 For elevating the members 34 and 35 to lift the box cover from the box after the elements 40 have been inserted thereunder, I provide two lifting bars 44 and 45 which have their upper ends positioned within recesses 46 in 15 the blocks 36 and 37 and arranged to abut against a wall 47 in each of said blocks, and which have their lower ends secured by hinges 48 to an oscillatory cross member 49. The cross member 49 is secured by hinges 50 20 to the frame members 11 and is provided at one end with a relatively long lever arm 51 by which it may be oscillated. In this way a compound lever movement is secured for lifting the members 34 and 35.

25 A trip element 52 is provided on the bar 45 for engaging with the lever 29 and tripping the same after the box cover has been lifted.

In the operation of this device, the box 20 is first properly positioned on the supports 30 18, while the members 22, 23, 34 and 35 are in withdrawn position. The lever 29 is then pressed down to straighten out the toggle formed by this lever 29 and the link 28. This moves the bottom ends of the members 22 and 35 23 apart, and moves the top ends of said members 22 and 23 and the bottom ends of the members 34 and 35 together, forcing the gripping elements 25 into the ends of the box, and forcing the cover-lifting elements 40 be-

40 tween the top edge of the box and the box cover as shown in Fig. 3. When the lever 29 is at the limit of its movement, the stop 33 will rest against the bottom of the lever 28 and the pivot 31 will have passed the center

45 line common to the two pivots 30 so that the two lever members 28 and 29 will be locked in this position. After the lever 29 has been fully depressed, the lever 51 will be moved to the right from the position shown in Fig. 1, 50 thus elevating the bars 44 and 45 and parts connected therewith and lifting the cover 21 from the box. As the bars 44 and 45 reach the limit of their upward movement, the trip element 52 will strike against the bottom side

55 of the lever 29 and move the pivot 31 below the line of centers common to pivots 30, thus permitting the weight 32 to move the box engaging and cover lifting parts to fully released position. This releases the cover, so 60 that the cover and the box may both be removed by the operator and another box inserted. As soon as the next box is in place, the lever 51 may be moved back to the position shown in Fig. 1, lowering the stops 42 so 65 that they rest on the top of the box and posi-

tioning the cover lifting elements for the next operation.

In the usual packing box the cover is nailed only at the ends and in those in which empty cans are shipped, small nails are used. These small nails pull easily and the heads of the same very seldom tear through the box cover. The tapered teeth of the element 40 ordinarily will not bend the nails even though they strike them, but said teeth will necessarily always be very close to the nails when the lift is exerted and will withdraw the nails by a straight lift in the easiest possible manner.

70 In Fig. 6 I have shown a modified form of the invention in which I provide an upright frame 54 having cross pieces 55, which support a trackway 56 for the reception of boxes 20, one only of which is shown. Mounted on pivots 57 at the sides of the trackway 56 are 75 two box gripping members 58, each having gripping elements 59 of the same form as the members 25, Fig. 4, secured thereto and adapted to grip the ends of the box. Levers 60 and 61 pivoted to the lower ends of the members 58 and to each other operate as toggle means to swing the members 58 on their pivots.

80 Cover lifting members 62 have their lower ends interlocked with the upper ends of members 58 for simultaneous swinging movement therewith and have their upper ends slidably supported between frame pieces 63 and rods 64. The members 62 have cover lifting elements 65 similar to the elements 40 of Fig. 5, 85 secured to their inner sides and arranged to enter between the top edges of the box and the box cover 21, and further have stops 66 provided thereon for engaging the top of the box to correctly position the elements 65. The 90 lifting means for the members 62 is in the nature of two angular levers 67 hinged at 68 and having their lower ends engaged beneath blocks 69 on members 62. The upper ends of the angular levers 67 are connected by links 70 with a hand lever 71 in the manner shown, so that the upper ends of the angular lever 67 may be moved outwardly simultaneously by movement of the hand lever 71 to thereby 105 raise the members 62 and lift the box cover 21.

110 In Figs. 7 to 10 inclusive, I have illustrated a fully automatic power operated machine of all metal construction for removing the box covers, removing the nails from said covers and disposing of the covers. In this machine the boxes are also fed into the machine and removed from the same by automatic means.

115 Referring to Figs. 7 to 10, I show a machine embodying a rectangular frame 72 of suitable shape and construction to support the operating parts of the machine. Mounted on the frame 72 are spaced parallel angle bars 73 forming a trackway for supporting boxes 74, 120 from which covers 75 are to be removed. The 125

boxes 74 are fed into and out of the machine by a reciprocating feed embodying parallel bars 76 movable longitudinally in guides 77 and having box engaging pawls 78 which are depressed when they are drawn rearwardly under the boxes and spring up as soon as they are released so as to engage behind the boxes and move said boxes forwardly when the bars 76 are advanced. The means for reciprocating the bars 76 is preferably in duplicate and includes links 79 connected with the bars 76 and with the upper ends of lever arms 80, which are pivoted as at 81 on the frame. The lever arms 80 are connected by adjustable means 82 with the outer ends of links 83. The inner ends of the links 83 are connected with crank pins 84 on discs 85 which are secured to a master cam shaft 86 that extends crosswise of the lower part of the frame. The links 79 are adjustable as to length by turnbuckles 87 to vary the positioning of the bars 76. The stroke of the bars 76 may be varied for different sized boxes by adjusting the means 82 to vary the point of connection of the link 83 with lever 80.

Two levers 88 and 89 have their bottom ends adjustably supported by pivots 90 and 91, which are secured to the frame, and their medial portions connected by short links 92 and 93 with the bars 76, whereby said levers 88 and 89 will be oscillated by movement of the bars 76 for the purpose of moving box lid supporting means of a form hereinafter described. The adjustable connections 91 make it possible to vary the throw of the top ends of the levers 88 and 89.

The means for gripping the boxes and for engaging with and removing the lids comprises two upright frame members 94 and 95 supported on opposite sides of the machine and pivoted for swinging movement from their bottom ends by pivots 96. Opposite to the ends of the boxes 74 the frames 94 and 95 are provided with transverse horizontal angle bars 97 upon which toothed box engaging elements 98 of a form similar to the elements 25 shown in Fig. 5 are secured for engaging with and gripping the ends of the boxes 74. The frames 94 and 95 are moved toward and away from the boxes 74 by forked levers 99, which are pivoted at 100 and have their upper ends connected with said frames by links 101. The lower ends of the levers 99 have rollers 102 which are disposed within suitable slots in cams 103 on the shaft 86, whereby the levers 99 will be oscillated as the shaft 86 rotates.

Movably mounted on the upper ends of the frame members 94 and 95 are slides 104 to which upper and lower horizontal angle bars 105 and 106 are secured. Cover removing elements 107 of a form similar to the elements 40 shown in Fig. 4 are secured to the lower angle bars 106 and arranged to enter between the top of the box 74 and the box cover 75 for lifting the box cover. Blocks or spacers 108 rest

on the top of the elements 107 and serve as a mounting means for horizontal stops or positioning members 109, which are bent upwardly at their outer ends to avoid jamming the edge of the cover and are adapted to rest on the top of a box cover and properly position the elements 107. The blocks 108 also serve as mountings for upright cover supporting brackets 110, which are narrow fingers. The upper angle bars 105 have upper cover supporting and nail pushing plates 111 secured thereto. The slides 104 are pivotally connected with the upper ends of upright push bars 112 which have rollers 113 on their lower ends arranged to roll on cams 114 on the shaft 86, whereby the slides will be moved vertically upward at the proper intervals in the cycle of operation of the machine. Said slides are arranged to be lowered by gravity when released by cams 114.

The nail pulling devices comprise shafts 115 disposed at each side of the machine and arranged to be oscillated through substantially one-half of one complete revolution by eccentric gear segments 116, which mesh with curved racks 117, which are guided in brackets 119 and are arranged to be moved vertically by links 120 that are connected with cranks 121 on shaft 122 having a gear wheel 123 which meshes with a corresponding gear wheel 118 on the shaft 86. Mounted on each shaft 115 are two U-shaped nail pulling members 124 and 125, slidably relative to each other, and having at their outer ends knife-like nail engaging elements 126. The hubs 100 of the members 124 and 125 are slotted as at 127 where they fit over the shafts 115 to permit longitudinal movement of said members and said hubs are provided with offset notches 128 and 129 that fit over cross keys 130 in the shafts 115, as more clearly shown in Figs. 9 and 10. When the shafts 115 are turned in the proper direction to swing the nail pullers toward the box cover, the keys 130 exert a pressure within the notches 128 and 129 which moves the members 124 and 125 slidably relative to each other, and spreads the nail grippers 126 apart, so that they may pass over the head of nails 131 which have been previously pushed up partially out of the box top, see Fig. 10, by the plates 111 as hereinafter described. As soon as the nail pullers reach the position shown in Fig. 10, the direction of rotation of the shafts 115 is reversed, the keys 130 draw the nail grippers 126 together, and clasp the nails, and further rotary movement of said shafts lifts the nails out and turns the nail grippers through an angle of substantially one hundred and eighty degrees. As soon as the nail grippers have pulled the nails, they will be out of the way during the remainder of the cycle of operation. The nails will either drop out by gravity when the nail pullers reach the reverse hori-

zontal position, or will drop out as soon as reverse movement of the shafts 115 begins in the next cycle of operation. The eccentric gears and curved racks constitute means for giving slow speed and more power when the nail is being pulled, and more speed and less power on other parts of the stroke.

A box top stacker for taking away and stacking the box tops is provided for operation in connection with the nail pullers. This box top stacker includes a shaft 132 having a driving connection by means of gears 133 and 134 with one of the shafts 115, so that it will always be oscillated in the opposite direction from the shaft 115 from which it is driven. Secured to the ends of the shaft 132 farther out than the nail pullers and so that they will clear the nail pullers at the sides are two arms, each formed of two members 135 and 136, of unequal length, that are slideable relative to each other. The shorter arm members 136 are connected at their outer ends by a cross bar 137 having a lip 138 arranged to engage beneath the end of a box cover, and the longer arms 135 are similarly connected by a cross bar 139 having a corresponding lip 140 thereon. The hubs of the arms 135 and 136 are slotted and notched in a manner substantially identical with the hubs of the nail pulling devices, whereby said arms are adapted to be moved slidably relative to each other by keys 141 in the shaft 132. When the nail pullers are fully retracted, the box top stacker will be resting on a box top from which the nails have just been removed, and the bars 137 and 139 will be spread apart so that the lips 138 and 140 underhang said box cover, said bars having been spread apart by the action of the keys 141 on their hubs as the box top stacker was swung inwardly over the machine. As soon as reverse movement of the shaft 132 begins, the bars 137 and 139 are drawn together and the lips 138 and 140 engage beneath the ends of the box cover, whereupon further reverse movement of said shaft 132 will swing the box cover through an arc as shown in Fig. 7 and finally deposit the same at a convenient distance from the machine. From the foregoing description it will be seen that the stacker is always moving oppositely from the nail pullers.

For the purpose of supporting the box covers after they have been lifted from the boxes and while the nails are being pushed and pulled out of the same, I provide three sets of supporting bars, namely, a lower set 142, a middle set 143, and an upper set 144. Each of these sets preferably comprises two spaced apart bars, positioned near the ends of the box cover, although it may comprise more bars or may be in the form of a single plate. The two lower sets of bars 142 and 143 are rigidly secured together and are movable simultaneously. The upper set of bars

144 is movable independently of the two lower sets. Suitable guides 145 on the frame support said bars for longitudinal sliding movement. The two sets of bars 142 and 143 are moved reciprocably into a retracted position by the lever 88, Fig. 8, which engages with a hook 146 on said bars. A spring 147 moves said bars inwardly when they are released by the lever 88 and dash pot means 148 cushions the inward movement of said bars. A trip member 149 is arranged to engage with the upper end of the hook 146 to release the same.

The upper set of bars 144 is moved into retracted position by the lever 89 which engages with a hook 150 on said bars and is moved inwardly over the box covers by a spring 151, dash pot or cushioning means being provided at 152 for absorbing the shock of the inward movement. A trip member 153 is provided for engaging with the upper end of the hook 150 to release the bars 144 at the proper time. The levers 88 and 89 adjustably pivoted at their lower ends constitute readily adjustable means for retracting the bars 142, 143 and 144 quickly at the proper time in the cycle of the machine.

Any suitable means, not shown, may be provided for driving the machine, as, for instance, a motor connected by suitable speed reduction gears with the gear wheel 118.

In the operation of the machine disclosed in Figs. 7 to 12, incl., the boxes 74 may be brought in by any suitable mechanism and deposited on the track members 73, where they will be picked up by the reciprocating feeder bars 76 and correctly positioned within the machine.

The cycle of operation of the machine is as follows, it being assumed that the machine has been started and that two box covers are supported on the respective sets of bars 142 and 143, and that a new box has just been brought into position by the feeder bars 76. As soon as the said box has arrived at the proper position, the cams 103 begin to move the frame members 94 and 95 inwardly, forcing the elements 98 into the ends of the box and forcing the cover lifting elements 107 between the box cover 75 and the top edge of the box 74, the curved positioning members 109 having first engaged the top of the covers 75 and properly positioned the members 107. The instant this inward movement is completed, the cams 114 will begin to lift the slides 104, carrying with them the elements 107 and lifting the cover from the box. While the gripping of the box and lifting of the cover has been taking place, the feeder bars 76 have been moving back to the left as shown in Fig. 8, and have retracted the bars 142 and 143, and the box covers 75, which were previously supported on the bars 142 and 143 respectively, have been allowed to rest on the fingers 110 and the plates 111 re-

spectively, the points of the nails in the upper box cover 75 resting on the plates 111 which are preferably milled finely on their top surfaces to prevent the nail points from slipping thereon and bending the nails. The box covers 75 will not be withdrawn along with the rods 142 and 143, because they are raised from said rods at the time the movement of the rods occurs.

10 Before the removal of the box cover is completed, the rods 142 and 143 will be entirely out of the way, thus allowing the cover just removed to be lifted and allowing the plates 111 to push the nails upwardly in the upper cover far enough so that they may be caught by the nail pulling devices, the bars 144 serving as stops on the upper side of the uppermost box cover, while the nails are being pushed out. As soon as the lifting devices reach their uppermost position, the bars 142 and 143 are released and are quickly moved by the springs 147 into a position under the two lowermost box covers, but the uppermost cover with the nails partly pushed out will be supported on the longer plates 111. At this same time the nail pullers, which have been previously moving toward the box top, will close over the nails and then begin their reverse movement.

15 20 Attention is called to the positions in Fig. 7 in which the box is gripped just previous to the lifting of the cover and the nail pullers are approximately midway of their stroke. As soon as the nail pullers have gripped the nails, they begin their return stroke first pulling the nails and eventually dropping them at approximately one-hundred and eighty degrees from the point they are pulled. After the nails have been pushed up by the plates 111 and the bars 142 and 143 released and permitted to move under the two lowermost box covers, then the cams 103 shift the levers 99 and move the frames 94 and 95 outward, releasing the box and the box cover.

25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

another cover, which is supported on the bars 143. Return movement of the stacking device will be completed while the next box is being gripped and the cover lifted therefrom and the hook 150 will be tripped and permit the return of the bars 144 before the lifting mechanism again moves upwardly.

The various operations are overlapping throughout substantially the entire cycle, but a cycle is completed at each revolution of the master shaft 86 and all of the operations are timed from this shaft. The movements are all simple and capable of being carried out in quick succession, making the machine very rapid in operation. The machine does not damage the boxes and removes the covers with the least possible breakage, thus economizing on boxes and box covers as well as saving much time and labor.

The term "sides" of the box, as herein used applies also to the ends of the box unless otherwise specified.

Obviously, changes may be made in the forms, dimensions and arrangement of the parts of my invention without departing from the principle thereof, the above setting forth only preferred forms of embodiment.

I claim:

1. A machine for removing box covers embodying means for gripping and holding a box; cover lifting devices arranged to be inserted underneath the edges of the box cover between the cover and the box cover engaging elements on said cover lifting devices for positioning the same; and means for elevating said lifting devices to remove the cover from the box.

2. A machine for removing box covers which are nailed onto wooden boxes embodying box supporting means; means for gripping and holding the box; means for applying and releasing said gripping means; thin sharp cover lifting elements supported at the sides of the box; means arranged to engage the top side of the cover for positioning said cover lifting elements in the plane of the bottom side of said cover; means for forcing said cover lifting elements between the cover and the top edge of the box; and means for moving the cover lifting elements away from the box to withdraw the nails and remove the cover.

3. A machine for removing box covers which are secured by nails to wooden boxes embodying means for supporting the boxes; laterally movable frames at the sides of the box supporting means; toothed box gripping elements on the inner sides of said frames; means for moving said frames laterally; cover lifting members at the upper ends of said frames movable laterally with said frames and movable vertically independently of said frames; cover engaging elements on said cover lifting members; and means

for moving said cover lifting members vertically.

4. A machine for removing nailed wooden box covers embodying box supporting trackways; upright members supported for sidewise swinging movement at the sides of said trackways; means for swinging said upright members toward and away from boxes that are supported on said trackways; means on said upright members for gripping said boxes; cover lifting members at the upper ends of said upright members, said cover lifting members being movable sidewise with said upright members and movable vertically independently of said upright members; cover engaging elements on said cover lifting members; and means for elevating said cover lifting members.

5. A machine for removing nailed wooden box covers embodying a main frame; a trackway on said main frame for supporting boxes; box holding members movably mounted at the sides of the trackway; box gripping elements on said box holding members; means for moving said box holding members sidewise to grip or release a box; cover lifting members at the top ends of said box holding members, said cover lifting members being movable vertically and horizontally; relatively thin cover lifting elements on said cover lifting members; and stop means on said cover lifting members above said cover lifting elements arranged to rest upon a box cover and position said cover lifting elements for insertion between the box cover and the top of a box upon which said cover is nailed.

6. A machine for removing the covers from boxes embodying box supporting means; box gripping devices disposed at the sides of said box supporting means; cover engaging and lifting elements disposed at the sides of said box supporting means and interconnected with said box gripping devices; mechanism for moving said box gripping devices and said cover lifting elements inwardly simultaneously into engagement with a box; and means for elevating said cover lifting elements independently while said box gripping devices remain engaged to lift the cover from the box.

7. A machine for removing box covers which are nailed onto wooden boxes embodying an upright main frame; trackways on said frame for supporting boxes; box holding members fulcrumed at the sides of said trackways; box gripping elements on the insides of said box holding members near their upper ends; means connected with the lower ends of said box holding members for oscillating the same to grip and release a box; vertically movable cover lifting members connected with the upper ends of said box holding members for sidewise move-

ment simultaneously therewith; cover engaging elements on said cover lifting members; and means for moving said cover lifting members vertically.

8. An automatic machine for handling wooden boxes having covers nailed thereon embodying means for gripping and holding the box; means for engaging the cover and lifting the same from said box by pulling the nails; means for pushing the nails up in said cover; means for grasping and pulling said nails; and means for removing said box cover after the nails are withdrawn.

9. In an automatic machine for handling wooden boxes which have covers nailed thereon, a main frame; box supporting trackways on said main frame; means at the sides of said trackways for gripping and holding a box; devices for operating said box gripping means; vertically movable means for engaging with and lifting a cover that is nailed onto a box; devices for operating said vertically movable means; devices for receiving and supporting said cover after it has been lifted from the box; and means for removing the nails from said cover.

10. In an automatic machine for handling wooden boxes having covers nailed thereon, a main frame; box supporting trackways thereon; means for advancing boxes by intermittent movements along said trackways; means at the sides of said trackways for gripping and holding a box; devices for operating said box gripping means; vertically movable means for engaging with and lifting a cover that is nailed onto a box; devices for operating said vertically movable means; devices for receiving and supporting said cover after it has been lifted from the box; means for removing the nails from said cover; and means for picking up said cover and disposing of the same.

11. An automatic machine of the class described embodying box supporting means; box holding members at the sides of said box supporting means; box gripping elements on said box holding members; means for moving said box holding members into and out of engagement with a box on said box supporting means; cover lifting members slidably on the top ends of said box holding members; cover engaging elements on said cover lifting members; and means for moving said cover lifting means vertically.

12. In an automatic machine of the class described, box supporting means; reciprocatable bars for advancing boxes along said box supporting means; a master cam shaft disposed below said box supporting means; means connected with said cam shaft for operating said bars; box holding members at the sides of said machine; means on said cam shaft for moving said box holding members into and out of engagement with a box on said supporting means; cover lifting members

- movable sidewise with said box holding members; means on said cover lifting members to engage beneath a box cover; means operated by said cam shaft for elevating said cover lifting members to lift the box cover from the box; means for receiving and supporting said removed box cover; means for removing the nails from said box cover; and a box cover stacking device for removing said box cover.
13. In an automatic machine of the class described, box supporting means; reciprocable bars for advancing boxes along said box supporting means; a master cam shaft disposed below said box supporting means; means connecting with said cam shaft for operating said bars; box holding members at the sides of said machine; means on said cam shaft for moving said box holding members into and out of engagement with a box on said supporting means; cover lifting members movable sidewise with said box holding members; means on said cover lifting members to engage beneath a box cover; means operated by said cam shaft for elevating said cover lifting members to lift the box cover from the box; means for receiving and supporting said removed box cover; means for removing the nails from said box cover; and a box cover stacking device for removing said box cover.
14. A machine for removing box covers which are secured by nails to wooden boxes embodying means for supporting the boxes; laterally movable frames at the sides of the box supporting means; toothed box gripping elements on the inner sides of said frames; means for moving said frames laterally; cover lifting members at the upper ends of said frames movable laterally with said frames and movable vertically independently of said frames; and means for moving said cover lifting members vertically.
15. A machine for removing box covers embodying oppositely disposed spaced apart box holding members movable toward and away from each other; box gripping elements on said box holding members; cover lifting elements connected with said box holding members for simultaneous sidewise movement therewith but independently movable longitudinally of said box holding members; means for moving said box holding members sidewise whereby said box gripping elements and said cover lifting elements are caused to engage a box, and independent means for moving said cover lifting elements longitudinally relative to said box holding members.
16. In an automatic machine of the class described, box supporting means; a master cam shaft disposed below said box supporting means; box holding members at the sides of said machine; means on said cam shaft for moving said box holding members into and out of engagement with a box on said supporting means; cover lifting members movable sidewise with said box holding members; means on said cover lifting members to engage beneath a box cover; and means operated by said cam shaft for elevating said cover lifting members to lift the box cover from the box.
17. In an automatic machine of the class described, box supporting means; a master cam shaft disposed below said box supporting means; box holding members at the sides of said machine; means on said cam shaft for moving said box holding members into and out of engagement with a box on said supporting means; cover lifting members movable sidewise with said box holding members; means on said cover lifting members to engage beneath a box cover; means operated by said cam shaft for elevating said cover lifting members to lift the box cover from the box; means for receiving and supporting said removed box cover; means for removing the nails from said box cover; and a box cover stacking device for removing said box cover.
18. In an automatic machine of the class described, box supporting means; a master cam shaft disposed below said box supporting means; box holding members at the sides of said machine; means on said cam shaft for moving said box holding members into and out of engagement with a box on said supporting means; cover lifting members movable sidewise with said box holding members; means on said cover lifting members to engage beneath a box cover; means operated by said cam shaft for elevating said cover lifting members to lift the box cover from the box; rod means arranged to be moved under said cover to support the same; devices for withdrawing said rod means while the cover is being lifted; other rod means disposed above said cover; means carried by the cover lifting devices for pushing the nails upwardly in said box cover; and means operated from said cam shaft for withdrawing the nails from said cover.
- In witness whereof, I hereunto subscribe my name this 24th day of July, 1928.
- CHARLES J. CARLSON.
